ABSTRACT: An electrically heated soldering iron includes a tubular body of two rigidly connected colinear parts, a bit and heater element at the front end of said body and a hollow handle at the rear end of said body. A thermostatic control is disposed within the body and includes a wire having a low coefficient of thermal expansion secured at its front end to a rear part of the bit and secured at its rear end to operating means for a switch in the handle. At least a part of the rear end of the bit is of a higher coefficient of thermal expansion than the effective coefficient of thermal expansion of said wire, and said wire is tensioned as the bit heats up to operate said switch means.

THERMOSTATICALLY CONTROLLED ELECTRIC SOLDERING IRON

BACKGROUND OF INVENTION

This invention concerns electrically heated soldering irons. The main object of the invention is to provide a construction in which the bit is maintained at a substantially constant predetermined temperature by means incorporated within the iron structure which interrupts the electric supply to the heating element when the bit attains a certain temperature, and reconnects the said supply when the temperature of the bit falls below a certain temperature. Thus the invention provides an iron in which the current flow is thermostatically controlled.

Another object of the invention is to provide a thermostatic control which is of a simple construction, and which can be incorporated in irons of small size. A further object is to provide an iron in which the control can be fitted easily or removed easily for repair. Yet another object of the invention is to provide a thermostatic control in which the operating temperature can be adjusted easily without dismantling the iron.

SUMMARY OF INVENTION

According to the invention the iron comprises a tubular body, a bit and heater element at the front end of said body, a hollow handle at the rear end of said body, a thermostatic control within the body, said control comprising a wire within said body and secured at its front end to a rear part of the bit, operating means for a switch in the handle to which means the rear end of the said wire is secured, at least a part at the rear end of said bit of a higher coefficient of thermal expansion than the effective coefficient of thermal expansion of said wire, said wire being tensioned as the bit heats up to operate said switch means.

The tubular body may constitute the said member, being all of a material of high thermal expansion such as copper or brass, but preferably said body has only a front part of such material, the remainder being of Invar steel, nickel iron alloy or like low expansion material. The rod or wire also preferably is of Invar steel, but again, only a front part of the rod or wire need be of this material.

The tube may constitute the main body or it may be within an outer casing, for example of close wound iron wire.

It will be appreciated that with the construction according to the invention, the switch is operated to interrupt the current to the element by tensioning of the rod or wire. This enables a thin rod or wire to be used so that irons of small size incorporating the thermostat control can be constructed.

BRIEF DESCRIPTION OF THE DRAWINGS

Two embodiments of soldering irons according to the invention will now be described with reference to the accompanying drawings, in which:

FIG. 1 is a sectional view of one embodiment.

FIG. 2 is a similar view partly in section, at a right angle to FIG. 1, and

FIG. 3 is a view similar to FIG. 1 of the second embodiment. Like numerals refer to like parts in all of the views.

DESCRIPTION OF PREFERRED EMBODIMENTS

Referring firstly to FIGS. 1 and 2, the iron has a wire wound outer body casing 10, handle 11, and a bit tip 12. The bit includes a rear hollow part 12a on to which the tip 12 engages, for example by screwthreads, which part 12a is mainly within the casing 10 and forms a part of the body, and a heating element (not shown) is wound (with suitable insulation) around the said part 12a.

The part 12a is of high expansion metal such as copper and

forms a colinear front part of a tubular body 14a within the casing 10, this tube being of Invar steel.

A wire 15 of low expansion metal such as Invar steel is within the body comprising the tube parts 12a and 14a, and is secured by means of a nut 17a at the front end. The rear end of the tube 14a is secured in a bush or boss 19 and a bell crank lever 23 is mounted on a support 20 secured to the bush by its pivot and within the handle 11, to one leg of which the rear end of the wire 15 is secured. The other leg of the bell crank 23 operates a microswitch 25. The angular setting of the bell crank can be adjusted by means of a screw 26, through a hole 26a through the handle 11. A line cord C is anchored in the handle by a grip screw 27, the leads being connected to pins mounted on the bush. The support bracket 20 is used for the mounting of the assembly including the body, so that by removing the screws 29, the complete assembly can be removed from the handle.

With the above construction, when the iron is cold the switch contacts make. As the iron heats up, owing to the differential expansion of the steel wire and front tube part 12a, the wire is tensioned until at the predetermined temperature the bell crank is moved sufficiently to press on the operating member of the switch 25 and open the switch contacts.

A neon indicator lamp N is connected through a suitable resistance in the circuit, so as to be energized when the heater element is energized. The handle 11 can be of a transparent or translucent synthetic plastics material.

In the embodiment illustrated in FIG. 3, the rod or wire 15 is within a brass or copper tube 14 which extends at its front end into a blind bore 12b in the bit, the wire end and tube end in this bore being secured together at 17. The tube 14 is within an outer tube 18 which is within the casing 10, and the tube 14 is secured by a nut 21 to the bush 19.

In this embodiment only a front part 15a of the rod or wire is of Invar steel. This construction could also be used in the embodiment of FIGS. 1 and 2.

The iron herein can be constructed easily and cheaply, and can be fitted into a tubular handle of small cross sectional area. The on/off switching action is rapid with little time lag from actual bit temperature, as the part 12a, FIGS. 1 and 2, or the front part of the tube 14, FIG. 3, is adjacent the heating element. Adjustment of the operating temperature also is possible without any dismantling of the iron.

We claim:

1. An electrically heated soldering iron comprising a tubular body of two rigidly connected colinear parts; a bit and an electrical heater element for said bit carried by a front one of said two colinear parts; a bush rigidly secured about a rear one of said two colinear parts; a hollow handle having an open end in which said bush is telescopically received, said handle rigidly secured to said bush to extend away from said rear one of said two colinear parts; a support member directly carried by said bush and positioned within said hollow handle; an electrical switch mounted on said support member and arranged to make and break the electrical supply to said heater element; an operating member pivotally mounted on said support member and arranged to operate said electrical switch; and a thermostatic control comprising a tensioned wire passing through said tubular body and being rigidly secured at its front end to said front one of said two colinear parts and rigidly secured at its rear end to said operating member, said wire having a lower coefficient of thermal expansion than at least said front one of said two colinear parts, whereby on heating of said heater element to a predetermined temperature, said wire is tensioned such as to cause said operating member to operate said electrical switch to break the electrical supply to said heater element, and on cooling of said heater element to below said predetermined temperature said wire is slackened sufficiently to release said operating member from said electrical switch to allow said electrical switch to remake the electrical supply to said heater element.
